UNITED STATES PATENT OFFICE.

JOHN W. NEWMAN, OF HENDERSONVILLE, NORTH CAROLINA.

PROCESS OF MAKING ORNAMENTAL MASONRY ARTICLES.

Application filed October 17, 1923. Serial No. 669,087.

To all whom it may concern:

Be it known that I, JOHN W. NEWMAN, a citizen of the United States, and resident of Hendersonville, county of Henderson, State of North Carolina, have invented an Improvement in Processes of Making Ornamental Masonry Articles, of which the following description, in connection with the accompanying drawings, is a specification, 10 like characters on the drawings representing like parts.

My invention aims to provide an improved process for making ornamental masonry articles.

15 The drawings disclose illustrative articles made in accordance with my invention, wherein—

Figure 1 is a side elevation of a finished article made in accordance with my invention;

20 Fig. 2 is a sectional elevation taken on the line 2—2 of Fig. 1, showing the article and also showing a mold for forming the article in mid-section; and

25 Fig. 3 is a fragmentary sectional view of an article of different shape made in accordance with my method.

Heretofore, it has been customary to make ornamental stone surfaces either by imbedding the stones or pebbles in the face of a wall or slab after it has been formed and permitted to "set" sufficiently to retain its shape, or by casting or pouring wet mortar over broken stones partially imbedded in a temporary layer or base of fine sand or other material in the bottom of a mold and then removing the sand from the exposed surfaces of the stones after the mortar is set. Repeated unsuccessful experiments 35 have demonstrated that neither of the foregoing methods is practical for making articles presenting convex or irregular outer surfaces. A pot or jar such as that shown in Fig. 1, for example, will not retain its shape after it is removed from a mold in the semi-plastic state prior to inserting or partially imbedding the broken stones or other decorative or surface forming bodies. Further, broken stones and the like cannot 40

45 be satisfactorily key-seated in interlocking relation in plastic or semi-plastic mortar after the body is formed. Articles having concave or convex outer surfaces cannot be cast according to the latter method, for the 50 reason that the temporary layer or base of sand will not cling to the wall of the mold

and support the stones in position. My improved method not only obviates the foregoing difficulties but makes it possible to produce articles having a great variety of 60 shapes and almost any desired external appearance, depending upon the color and character of the imbedded pieces.

In accordance with my preferred method, as practiced for making a pot or jar 4 such as is shown in Fig. 1, I employ a suitable form or mold A (Fig. 2) to produce the desired external shape of vessel. A layer of the plastic mortar 5 which may consist of sharp sand and cement, is placed in the 70 bottom of the mold to form the flat bottom of the vessel, and then broken stones or other hard material of suitable size are laid by hand in two or more rows or tiers, one upon the other, and supported against the 75 inner periphery of the form; each stone resting upon and in contact with the layer below. Plastic mortar, cement or similar material of such consistency that it will not flow freely is then applied, preferably by 80 hand with a suitable tool, such as a trowel, and gently pressed into the interstices or crevices between the stones; care being taken not to force it entirely through the openings against the inner surface of the mold. 85 After the mortar has been applied against the interior faces of the bottom layers of stones, the process is repeated until the completed article is formed. The interior surface may be finished or smoothed over 90 gently by hand to produce the desired shape, a very rich mixture of cement preferably being employed. After the article has been allowed to set or harden sufficiently to retain its shape, it may be removed from the 95 mold, and requires no further treatment other than brushing to remove loose dirt and particles of stone and mortar.

In Fig. 3, I have shown the manner of making plain flat or curved slabs 7 which form a part of many ornamental articles. I employ a suitable form B supported in an inclined position whereby to prevent the successive layers of loose stones 8 from falling down, and to prevent the mortar, after it is applied, from penetrating or settling through the interstices against the surface of the form. The method of forming the slab is, in all other respects, the same as that employed in making pots or jars as hereinbefore described.

It will be seen that, in accordance with

my invention, the stones are actually incorporated with and firmly seated in the mortar while it is in the plastic state, and very little of the mortar is visible in the small spaces between the stones. Also, none of the mortar is permitted to smear the exterior faces of the stones, thereby contributing to a decorative appearance.

Obviously the invention is not limited to the specific steps described in connection with the process, nor to the illustrative articles made in accordance therewith, but is susceptible of various changes and modifications to suit the purposes to which it is applicable.

Having thus described my invention, what I claim and desire to secure by Letters Patent is:

1. The method of making ornamental masonry articles which comprises laying progressively a plurality of tiers of face stones against a mold face substantially removed from the horizontal; applying to the faces of the stones of each tier as formed a plastic backing of low fluidity; pressing such backing material between said stones

to anchor the latter but not sufficiently to fill the interstices therebetween; finishing the interior surface of said backing material; permitting it to set and removing the finished article from the mold.

2. The method of making ornamental masonry articles having curved outer walls which comprises laying progressively a plurality of tiers of stones of irregular shapes against the surface of a mold each in physical contact with its neighbor; applying to the backs of said stones of each tier as formed a plastic cementitious backing of suitable consistency; pressing said backing material into the interstices between the stones partially to fill the same whereby to anchor some of the stones in interlocking relation in said backing; applying a finishing layer of relatively fine cementitious material to said backing and shaping the interior of said article; and permitting said cementitious material to harden in the mold.

In testimony whereof, I have signed my name to this specification.

JOHN W. NEWMAN.
